United States Patent Office.

HORACE BONHAM, OF PHILADELPHIA, PENNSYLVANIA.

Letters Patent No. 105,895, dated August 2, 1870.

IMPROVEMENT IN HEAD-MEASURE FOR HATTERS.

The Schedule referred to in these Letters Patent and making part of the same.

To all whom it may concern:

Be it known that I, HORACE BONHAM, of the city and county of Philadelphia and State of Pennsylvania, have invented a new and improved Cephalic-Meter; and I do hereby declare that the following is a full, clear, and exact description of the same, reference being had to the accompanying drawing forming a part of this specification, in which—

Figure 1 is a perspective view, and

Figures 2 and 3 sectional elevations of two different constructions of my meter.

The object had in view in making this invention was the production of an apparatus by which to take the exact outline of the human head, for the purpose of facilitating the fitting of hats.

The invention consists of a band of lead or such other material as can be readily bent to conform to the shape of the head, and such as retains any form which may be given it, such band being covered with leather and combined with a socket furnished with a set-screw, and attached to one end of the band, and with a graduated tongue fastened to the other end of the band, which tongue enters the socket and may be clamped therein by the set-screw, so as to retain the measurements after they have been obtained.

In the drawing—

a is the leaden band.
b the leather covering.
c the metallic socket, attached to one end of the covering *b*.
d the graduated tongue, fastened to the opposite end of the leather covering.

In fig. 2 the leather covering merely incloses the leaden band, but in fig. 3 the leather covering extends above the leaden band, so as to form an upper leather band, *e*, which is fastened together at its top edge by binding, *f*.

After the band has been fitted to the head it is to be placed on paper, and the shape traced along its inner edge with a pencil.

Having thus described my invention,

What I claim as new, and desire to secure by Letters Patent, is—

The band *a*, of lead or other flexible metal, combined with the covering *b*, socket *c*, and graduated tongue *d*, substantially as and for the purpose specified.

HORACE BONHAM.
